United States Patent Office.

STEPHEN D. ARNOLD, OF NEW BRITAIN, CONNECTICUT, ASSIGNOR TO P.
AND F. CORBIN, OF SAME PLACE.

Design No. 3,049, dated May 26, 1868.

DESIGN FOR A CUPBOARD-LATCH.

The Schedule referred to in these Letters Patent and making part of the same.

TO ALL WHOM IT MAY CONCERN:

Be it known that I, STEPHEN D. ARNOLD, of New Britain, in the county of Hartford, and State of Connecticut, have invented or produced a new and original Design for Latches for Cupboards; and I do hereby declare the following to be a correct description of the same, reference being had to the annexed photograph of the parts composing said latch.

Figure 1 represents the design of the shape and configuration of the catch or nosing.

Figure 2 shows the latch itself with the porcelain button.

Figure 3, the screw that passes through the end of the latch, and on which it swings.

Figure 4 shows the plate of the latch, to which my invention especially relates.

The shape and configuration of the top, bottom, and inner end of this latch-plate are determined by the scrolls and leaves forming the ornamental surroundings of the plate.

The front or outer edge of said plate is nearly straight, but formed with a raised bar, *a*, behind which the latch, fig. 2, is passed, and within this the plate is formed with a semicircular configuration, *b*.

The shape of the opening *c*, through which the screw, fig. 3, passes, is that of two half circles united by straight or nearly straight lines, so as to be elliptical.

The screw-holes *i i* are round.

What I claim, and desire to secure by Letters Patent, is—

The design of the shape and configuration of the latch-plate, as described, and shown in fig. 4.

In witness whereof, I have hereunto set my signature, this seventh day of April, A. D. 1868.

Witnesses:

CHARLES PECK,
R. S. PORTER.

S. D. ARNOLD.
